UNITED STATES PATENT OFFICE.

DAVID S. WHITE, OF NORTHFIELD, ASSIGNOR TO J. B. MALING, OF MINNEAPOLIS, MINNESOTA.

HOISTING-MACHINE.

SPECIFICATION forming part of Letters Patent No. 508,155, dated November 7, 1893.

Application filed February 27, 1893. Serial No. 463,907. (No model.)

To all whom it may concern:

Be it known that I, DAVID S. WHITE, a citizen of the United States, residing at Northfield, in the county of Rice and State of Minnesota, have invented certain new and useful Improvements in Hoisting-Machines; and I do hereby declare the following to be a full, clear, and exact description of the invention, such as will enable others skilled in the art to which it appertains to make and use the same.

My invention relates particularly to an improvement in the type of hoisting machines which are shown and described in Letters Patent No. 461,005, granted to me October 13, 1891. Machines of this general character are of especial value in digging sewers and ditches, and in other similar work, where it is desirable to lift the load from the ditch and carry it back from said ditch before it is dumped.

The principal object of the present invention is to provide a construction with which the load, after being lifted, may be quickly carried away from the ditch a greater distance than is possible with the machine shown in the before mentioned patent, and with which the parts may be very quickly returned to the position in which the bucket when lowered will descend into the ditch.

Another object of the improvement shown is to brace the sliding derrick arm, so that it will not be bent when the load is being lifted.

In the drawings, Figure 1 is an end elevation of a hoisting machine containing my invention, and Fig. 2 is a front view of the same.

The apparatus includes a supporting framework A of suitable height, which I prefer to mount on a wheeled truck H, whereby the apparatus may be conveniently moved from place to place.

Hinged to the upper part of the framework A is a swinging derrick member, which as shown, consists of the arm B adapted to overhang the framework, and the rearwardly projecting arm B'. The arm B consists of two connected parallel arms b b, and each of these is connected by means of a brace B² with the arm B'. Two other arms B³ B³ are connected at their lower ends with the braces B² and at

their outer ends with the outer end of the arm B. The parts B³ are in effect a part of the arm B, and they might be omitted providing the pieces forming the arm B were made wide enough to accommodate the rollers c c' to be presently explained.

In the upper end of the arm B the sliding derrick arm C is mounted in substantially the same manner that the similar arm is mounted as shown in the prior patent hereinbefore referred to; that is to say, the arm itself is curved and rests on a grooved roller c' which is mounted in the outer end of the said arm B. A second roller c² is also mounted in the arm B and lies above and bears against the upper side of the sliding derrick arm. On the inner end of the sliding derrick arm is formed a hook or stop, which, when said arm is projected as far as is desirable, engages with the roller c² and prevents further outward movement of said sliding arm. A sheave c³ is secured to the outermost end of the sliding derrick arm, and the hoisting rope I passes over this sheave, and over the elevated sheave F, which is mounted on the upper ends of the pieces D D, which are secured to the framework A.

The arm B' lies beneath a fixed stop E, and, when the swinging derrick member is at the limit of its outward movement, this arm strikes against said stop, whereby the further forward movement of said swinging member is prevented.

G represents a spring made up of a series of elliptical springs g, the lower one of which rests upon a crossbar a on the framework. The upper elliptical spring is secured to a bar G', the upper end of which is hinged to the under side of the arm B', and which passes loosely through the crossbar a, whereby said bar is guided. When the swinging derrick member is swung backward, the arm B' moves downward, and in so doing, compresses the spring G. This spring therefore resists the backward movement of the swinging derrick member and acts in some degree as a cushion to prevent injurious jar. When the swinging derrick arm is at the limit of its backward movement, the arm B' engages with the framework A, which acts as a stop. When the hoisting rope I is slackened, the spring G,

by acting upward against the arm B', causes the swinging derrick member to so swing as to carry the upper end of the arm B outward and away from the framework.

- 5 Fig. 1 in full lines represents the position the parts would occupy relative to each other, when the bucket has been lifted vertically out of the ditch. A stop *i* on the hoisting rope, engages with the outer end of the arm C and prevents the further movement of the hoisting rope over the sheave *c*³. A further pull upon the hoisting rope first causes the sliding arm to move upward and backward over the rollers *c c'* until the bracket *c'*⁴ strikes 10 the upper and outer end of the arm B. A further pull upon the cable causes the swinging derrick member to swing back on its hinge, after which the parts occupy the relative position shown by the dotted lines in 15 Fig. 1. At this point the bucket may be dumped in a car or cart, which rests upon the ground between the base of the hoisting apparatus described and the mouth of the ditch. It will be noticed that by the employment of 20 the swinging derrick arm in connection with the other parts as described, the bucket is moved farther back from the mouth of the ditch than it is in the apparatus shown in the prior patent mentioned. I am thus able to 25 support the apparatus in a position farther back from the mouth of the ditch than I otherwise could, whereby there is less danger that the weight of the apparatus will cause the walls of the ditch to cave in, and there is 30 also more room between the base of the apparatus and the mouth of the ditch for the car or cart, which is usually employed to carry the 35 dirt away.

In order to prevent the weight of the load 40 in the bucket from bending the sliding arm C, I pivot to the outer end of said arm, a brace K, composed of two parallel bars *l*. These bars are connected by a pin which lies in an inclined slot *a*³ on the upper edge of 45 the frame A. This brace does not in any way interfere with the described action of the parts, but it does prevent the load from bending the arm C.

Having described my invention, I claim—

- 50 1. In a hoisting machine, in combination, a supporting framework, a movable derrick member hinged to said framework, having an arm B which is adapted to overhang said framework, and rearwardly extended arm B',

a stop with which the upper side of said arm B' is adapted to engage a spring thrusting against the framework and against said arm B', whereby said arm is moved against said stop, a sheave in the outer end of said arm B, an elevated sheave carried by said frame, 55 a hoisting rope which passes over said two sheaves, and a stop on said rope adapted to engage with the swinging derrick member to swing it inward, substantially as and for the purpose specified. 60

2. In a hoisting machine, in combination, a supporting framework, a swinging derrick member hinged to said framework having the overhanging arm B and the rearwardly extended arm B', a bar G' hinged to said arm B', a guide for said arm, a spring secured to the framework and to the bar G', a sheave in the outer end of said arm B, an elevated sheave F, and a hoisting cable passing over said sheaves having a stop adapted to engage 70 with the arm B, substantially as and for the purpose specified. 75

3. In a hoisting machine, in combination, a supporting framework, a movable derrick member hinged thereto having an arm B 80 adapted to overhang said framework, a spring arranged to move the swinging derrick member to carry said arm outward, a sliding derrick arm mounted in the outer end of the arm B, having a sheave in its outer end, an 85 elevated sheave supported by said framework, stops limiting the movement of the swinging derrick member, stops limiting the movement of the sliding derrick arm in the arm B, a hoisting rope which passes over said 90 two sheaves, and a stop carried by said rope and adapted to engage with the outer end of said sliding arm, substantially as and for the purpose specified. 95

4. In a hoisting machine, in combination, 95 a supporting framework, an overhanging arm supported thereby, a sliding derrick arm, and a brace pivoted at its outer end to the outer end of said sliding derrick arm and having at its inner end a pin which lies in a slot in 100 said framework, substantially as and for the purpose specified.

In testimony whereof I affix my signature in presence of two witnesses.

DAVID S. WHITE.
